UNITED STATES PATENT OFFICE.

JACOB S. GIBBS, OF HARTFORD, CONNECTICUT, ASSIGNOR TO THE PERKINS ELECTRIC SWITCH MANUFACTURING COMPANY, OF SAME PLACE.

CUT-OUT.

SPECIFICATION forming part of Letters Patent No. 450,101, dated April 7, 1891.

Application filed February 11, 1891. Serial No. 381,091. (No model.)

To all whom it may concern:

Be it known that I, JACOB S. GIBBS, a citizen of the United States, residing at Hartford, in the county of Hartford and State of Connecticut, have invented certain new and useful Improvements in Cut-Outs, of which the following is a full, clear, and exact specification.

The invention relates to the class of cut-outs for multiple incandescent lamps having a base bearing pole pieces or contacts for the main leads of the circuit and a detachable cap bearing lamp-wire connections and safety-fuses.

15 The object of the invention is to provide a simple, cheap, and durable cut-out of this class, wherein the cap can be easily and quickly removed from or replaced on the base, to which it fits tightly with sure and close 20 joints between the conducting-contacts, without disturbing the main-circuit wires.

Referring to the accompanying drawings, Figure 1 is a central section of the cut-out. Fig. 2 is a plan view of the base and the contact-pieces with the cap removed. Fig. 3 is a plan view of the inside of the cap.

In the views, the letter *a* indicates the base, that is preferably formed circular, of porcelain, composition, wood, or any similar insulating material, having upon its back raised portions *a'*, so that when it is secured to a wall or ceiling an air-space is left between the base and support to prevent the collection and absorption of moisture. To opposite 35 edges of the front of the base are secured the pole-pieces or conducting-contacts *b*, to which the leads or main-circuit wires of the system are attached. The outer ends of these pole-pieces, which are forked for the reception of 40 the leads, are provided with binding-screws for clamping the leads to the pole-pieces to insure a good contact, while the inner ends are inclined or turned upward at any desirable angle—that is, not a right angle—with 45 the plane of the base. It is preferred that these pole-pieces be formed in two pieces, one of which *b'* has its outer end bent to form one portion of the fork, while the other *b''* is bent

at the outer end to form the complementary portion of the fork which bears the binding-screw *b''*, and bent at its inner end to form the upward-inclined contact *b'*. These two parts are usually held together to the base by a single screw, and, if desired, one part may be slightly curved, so that when the screw *b''* is forced against the lead the inner end *b'* rocks inward.

The cap *c*, which is usually made of a similar material as the base, is provided with conducting pieces or contacts *d*, secured to the inside of the cap by any common means. The ends of these contacts are preferably bent on the arc of a circle concentric with the center of the cap, and these circular ends *d'* are turned outward at an angle from the cap similar to that which the ends *b'* of the pole-pieces form with the base. These contacts are so attached to the cap that when the cap is placed over the base and given a slight turn the inclined ends *d'* of the contacts upon the cap pass beneath the inclined ends *b'* of the pole-pieces on the base, so as to dovetail together and hold tightly, making a close contact between the conducting parts and holding the cap securely and tightly to the base.

Held by suitable binding-screws safety-fuses *e* join the contact-pieces *d* with the contact-pieces *f*, to which, by binding-screws, are secured the lamp-leads that pass from these pieces *f* through the opening *c'* in the center of the cap to the lamp. Small pieces or projections *c''* are formed upon the inner edge of the rim of the cap to prevent the dovetailed contacts from passing beyond each other when the cap is turned upon the base.

The base is secured to a wall or ceiling by any suitable means and the leads of the main circuit attached to the pole-pieces. The lamp-leads are secured to the inside of the cap and suitable fuses inserted to complete the circuit. The cap is then placed over the base and a slight turn engages the inclined projecting contact-pieces projecting from the base and cap and so dovetails them together that the cap is held tightly to the base and a close contact is insured between the conduct-

ing parts. To replace a fuse, a slight turn of the cap disengages the dovetailed part and the cap is free to be removed.

The cut-out is simple, cheap, durable, and efficient.

5 I claim as my invention—

1. A cut-out consisting of a base bearing pole-pieces the inner ends of which project at an angle with the plane of the base, and a cap bearing conductors the ends of which project at a similar angle with the ends of the pole-pieces upon the base, substantially as described, and for the purpose specified.

15 2. A cut-out consisting of a base bearing pole-pieces the inner ends of which project at an angle with the plane of the base, and a cap bearing conductors the ends of which project at a similar angle with the ends of the pole-pieces upon the base, with safety-fuses

20 between the angularly-projecting contacts upon the cap and the binding-screws for the

attachment of the lamp-leads, substantially as described, and for the purpose specified.

3. A cut-out consisting of a base bearing pole-pieces having forked outer ends bearing binding-screws and inclined inner ends, and a cap bearing conductors with inclined inner ends formed upon the arc of a circle, substantially as described, and for the purpose specified.

30 4. A cut-out consisting of a base bearing pole-pieces formed in two parts, the outer ends of which form a fork and bear binding-screws, while the inner ends of one of which is inclined outward from the base, and a cap bearing conductors that incline at an angle from the plane of the cap, substantially as described, and for the purpose specified.

JACOB S. GIBBS.
